INFRARED HEATER

Joseph Gialanella, Newark, N. J., assignor to Thermex Company, Inc., Harrison, N. J., a corporation of New Jersey

Application January 11, 1954, Serial No. 28,447

Term of patent 14 years

(Cl. D81—10)

To all whom it may concern:

Be it known that I, Joseph Gialanella, a citizen of the United States, residing at Newark, in the county of Essex and State of New Jersey, have invented a new, original, and ornamental Design for an Infrared Heater, of which the following is a specification, reference being had to the accompanying drawings, forming part thereof.

In the drawings:

Fig. 1 is a front elevation view of an infrared heater showing my new design;

Fig. 2 is a side elevation view looking from the right side of Fig. 1;

Fig. 3 is a rear elevation view; and
Fig. 4 is a top plan view.

I claim:

The ornamental design for an infrared heater, substantially as shown.
